ATTORNEY.

UNITED STATES PATENT OFFICE.

ALBERTO CIMOROSI, OF ELETON, MARYLAND.

FUSE.

Application filed April 22, 1926. Serial No. 103,675.

My invention relates to fuses of the type used for signal purposes and its objects are to provide a fuse of simple and inexpensive construction, a fuse which, when thrown 5 against the earth or any solid substance, will be automatically ignited by the impact, and a fuse which is protected against accidental ignition.

These objects, and other advantageous ends which will be described hereinafter, I attain in the following manner, reference being had to the accompanying drawings in which

Figure 1 is a side elevation of a fuse embodying my invention as it appears when ready for the market,

Figure 2 a longitudinal central section of the same, and

Figure 3 an enlarged fragmentary longitudinal section showing the manner of ignition.

Referring to the drawings, the numeral 1 indicates a tube which encloses at one end, which for convenience will be called the inner end, a stud 2 preferably of wood which 25 may be glued to the interior of the tube. A wall 3, preferably of clay, closes the tube, but leaves a space 4 between it and the inner end of the stud. The stud has a central bore 5 in its enclosed end which communicates 30 with a smaller bore 6 extending through the other end. A plunger 7 having a pointed end is slidably mounted in bore 6 with its head 8 in bore 5. A cap 9, of the type which 35 explodes by impact, is placed in bore 5 above the head of the plunger and the outer part of the bore is partly closed by a tubular stop member 10 which may be of wood. The length of stop member 10 is such as to 40 leave a space 11 between the inner end of the tube and the head of the plunger. A fuse 12, having one end in space 4, extends 45 through a hole in the wall of the tube, then alongside the tube and enters the tube at its outer end. That part of the tube which is 50 between its outer end and wall 3 is filled 55 with readily ignitable material which is held therein by closing the outer end of the tube with paper or like material. To guard 60 against accidental inward movement, plunger 7 is held in its idle position, as shown in Figure 2, by a wad 13 of wax or other material which will adhere to the plunger and stud but will break when subjected to material force. The stud has an annular enlargement 14 which, when the fuse is as-

sembled, abuts the end of tube 1 and insures proper spacing. A cap 15 encloses the free end of the stud and its open end abuts the lower end of enlargement 14. A band 16 surrounds the enlargement and the ends of 60 the tube and cap and is glued thereto.

The fuse is assembled by inserting the plunger in the bore of the stud, placing the explosive cap over the head of the plunger, inserting stop member 10, securing the stud 65 in the tube and applying the cap to the stud and securing it thereto by means of band 16.

For use, as for example a railway signal, cap 15 is torn from the stud and the fuse thrown, preferably against a railway tie, 70 plunger foremost. The point of the plunger will be imbedded in the earth and hold the fuse in a substantially upright position. The impact will disrupt the adhesive wad 75 13 and force the plunger head upward thereby forcing the ignition cap against tube 10 thereby exploding the cap. The flame due to the explosion will ignite the fuse and the fuse will ignite the combustible material in the tube.

While I have described my invention as taking a particular form, it will be understood that the various parts may be changed without departing from the spirit thereof, and hence I do not limit myself to the precise construction set forth, but consider that I am at liberty to make such changes and alterations as fairly come within the scope of the appended claims.

Having thus described my invention, what 80 I claim as new and desire to secure by Letters Patent is:—

1. A fuse including a tube; a stud having one end secured within one end of the tube; a partition in the tube spaced from the enclosed end of the stud; a fuse leading from the space between the stud and the partition to the free end of the tube; combustible material in the tube; a pointed plunger slidably mounted in the stud; a hollow stop member 95 limiting the slidable movement of the plunger, and an explosive cap disposed between the head of the plunger and the stop member.

2. A fuse including a tube; a stud having one end secured within one end of the tube; 100 a partition in the tube spaced from the enclosed end of the stud; a fuse leading from the space between the stud and the partition to the free end of the tube; combustible material in the tube; a pointed plunger slidably 110

mounted in the stud; a hollow stop member limiting the slidable movement of the plunger; an explosive cap disposed between the head of the plunger and the stop member, and readily breakable means for locking the plunger in its idle position.

3. A fuse including a tube; a stud having one end secured within one end of the tube; a partition in the tube spaced from the enclosed end of the stud; a fuse leading from the space between the stud and the partition to the free end of the tube; combustible material in the tube; a pointed plunger slidably mounted in the stud; a hollow stop member limiting the slidable movement of the plunger; an explosive cap disposed between the head of the plunger and the stop member, and a cap enclosing the free end of the plunger and removably secured to the stud.
- 15 4. A fuse including a tube; a stud having one end secured within one end of the tube and having an enlargement, intermediate its ends, abutting the end of the tube; a partition in the tube spaced from the enclosed end of the stud; a fuse leading from the space between the stud and the partition to the

free end of the tube; combustible material in the tube; a pointed plunger slidably mounted in the stud; a hollow stop member limiting the slidable movement of the plunger; an explosive cap disposed between the head of the plunger and the stop member; a cap enclosing the free end of the plunger and abutting the enlargement, and a band enclosing the enlargement and adhesively secured to the ends of the tube and the cap.

5. A fuse including a tube; a stud having one end secured within one end of the tube and having a central bore of two diameters; a partition in the tube spaced from the enclosed end of the stud; a fuse leading from the space above the stud to the free end of the tube; combustible material in the tube; a pointed plunger slidably in the stud and having its head in the bore of larger diameter; an explosive cap disposed in said bore above the plunger head, and a hollow stop member secured in the larger bore and spaced from the inner end thereof.

In testimony whereof I have signed my name to this specification.

ALBERTO CIMOROSI.
